DESIGN FOR A PLATE

Jeddia B. Clark, Dunkirk, Ind., assignor to Indiana Glass Company, Dunkirk, Ind., a corporation of Indiana

Application October 29, 1935, Serial No. 59,262

Term of patent 7 years

To all whom it may concern:

Be it known that I, Jeddia B. Clark, a citizen of the United States, residing at the city of Dunkirk, in the county of Jay and State of Indiana, have invented a new, original, and ornamental Design for a Plate, of which the following is a specification, reference being had to the accompanying drawing, forming a part thereof.

Figure 1 is an inverted plan view of the plate; and

Figure 2 is a transverse, vertical sectional view of the plate, taken in the plane indicated by the line 2—2 of Fig. 1.

I claim:

The ornamental design for a plate, as shown. Dated at Dunkirk, Indiana, this 23rd day of October A. D. 1935.

JEDDIA B. CLARK.
